his Atty.

UNITED STATES PATENT OFFICE.

PETER NEUKIRCHEN, OF CHICAGO, ILLINOIS, ASSIGNOR TO COLUMBIA FASTENER COMPANY, OF CHICAGO, ILLINOIS, A CORPORATION OF ILLINOIS.

COMBINED DISPENSING-RECEPTACLE AND SPREADER.

1,373,566.

Specification of Letters Patent. Patented Apr. 5, 1921.

Application filed March 29, 1919. Serial No. 286,140.

To all whom it may concern:

Be it known that I, PETER NEUKIRCHEN, a citizen of the United States, and a resident of Chicago, Cook county, and State of Illinois, have invented certain new and useful Improvements in Combined Dispensing-Receiptacles and Spreaders, of which the following is declared to be a full, clear, and exact description.

10 This invention relates to combined dispensing receptacles and spreaders, and its principal object is to provide means whereby various mobile commodities may be readily poured out of a container in small quantities. Another object is to provide means whereby certain commodities, such as adhesives, and mucilages, may be dispensed from the container and spread about upon the surface upon which they are poured.

20 Another object is to provide a very simple, practical cap for the mouth of a receptacle, with a self-contained spring-pressed valve for closing a discharge opening in the cap, and to provide the cap with a flat surface, by means of which adhesives or mucilages may be readily spread about upon the surface upon which they are deposited.

The invention consists in the several novel features hereinafter fully set forth and more particularly defined in the claims.

The invention is clearly illustrated in the accompanying drawing in which:

Figure 1 is a perspective view of a combined receptacle and spreader, embodying a simple form of the present invention;

Fig. 2 is a side elevation thereof partly broken out to illustrate the interior construction;

Fig. 3 is a cross section taken on the line 40 3—3 of Fig. 2;

Fig. 4 is a plan of the valve and its spring support;

Fig. 5 is a perspective view of a slightly modified form of valve and spring;

Fig. 6 is a fragmental sectional view of a second modification; and

Fig. 7 is a perspective view of a fragment of the valve support seen in Fig. 6.

Referring to said drawing, the reference character 6 designates a container of any suitable form, here shown as comprising a glass bottle having an externally screw-

threaded neck 7 at its open end, upon which neck is secured a cap or closure 8, here shown as formed with a screw-threaded portion 9, arranged to be screwed upon the screw-threaded neck 7. Obviously, other expedients may be used for removably securing the cap to the bottle as is well known to those skilled in the art to which this invention pertains. The screw-threaded portion 9 is formed with an annular shouldered portion 10, between which and the upper edge of the neck of the bottle, is interposed a washer 11, of cork or other resilient packing material, whereby a tight joint may be made between the bottle and cap to prevent leakage around screw-threaded connection therebetween. From the shouldered portion 10 extends a tapering end portion 12 which is centrally apertured, as at 13, for the escape of the contents and said aperture is closed by a valve 14, which has a tip 15 protruding through the aperture, which tip may be pressed upon an object to unseat the valve. The valve has a flaring skirt portion 16 which seats against the inner edge of the apertured portion of the part 12 and closes the discharge aperture.

The valve 14 is retained on its seat by a spring support 17 which is made from a piece of spring wire bent into a ring-like base portion 18, one end of which is coiled into a spring coil 19 that terminates in an upwardly extending stem 20 that is secured to the valve 14 in any desirable manner. In the preferred form said coiled spring portion 19 is shown as extending in a vertical direction and the base portion 18 and coiled spring portion 19 are connected by a short piece 21 of the wire. An annular groove 22 is formed at the shouldered portion 10 of the cap, which groove may be formed by rolling the material outwardly to form a projecting annular bead, and the ring-like base portion 18 of the valve support seats in said groove and is held therein by its own elasticity. At the place where the short part 21 of the spring support extends from the base portion 18 to the coiled spring portion 19, the shouldered portion 10 of the cap is formed with a notch or groove 23 (see Fig. 8) to receive said short piece 21, whereby the shouldered portion of the

cap may have an even bearing all around upon the washer 11, except where the wire passes from the base portion 18 to the coiled spring portion 19. It is obvious that pressure upon the tip 15 of the valve 14 will unseat the said valve against the spring pressure.

The exact shape of the tapering end portion 12 is immaterial and it is here shown 10 as having a slightly curved side. The spreader is formed by striking up said tapering portion with suitable dies to form a flat part 24 which may extend from the apertured end of the cap to a place adjacent 15 the shoulder portion 10. This flat portion 24 provides a flat surface which may be readily used to spread adhesives or other mucilage upon any surface upon which they are deposited.

20 In the modified form of the invention shown in Fig. 5 the spring support 17^a has the ring-like base portion 18^a and a stem 20^a fastened to the valve 14^a. In place of the coiled spring 19 shown in the preferred 25 form, the base portion is extended inwardly toward the middle of the base portion, as shown at 21^a and bent upon itself in a vertical plane, to form a spring-like U-shaped portion 19^a. As in the preferred form, the 30 ring-like base portion seats in the groove 22 in the cap and the U-bend 19^a affords sufficient tension to yieldingly retain the valve upon its seat around the discharge aperture of the cap.

35 In the modification shown in Figs. 6 and 7 the valve is in the form of a ball 14^b and is kept on its seat by the spring support, the stem 20^b of which is curled around, at its upper edge to form a loop or ring 40 20^c for receiving the ball. To prevent spreading of the ring 20^c, a cup 14^c may be employed for holding the ball, and the edges of the cup may be curled around the loop or ring 20^c. The cup forms a seat in 45 which the ball may roll, and consequently, in using the device, the ball may be depressed to allow the contents to escape and the tip may be rubbed along the object upon which the contents are deposited, thus initially spreading them before further spreading 50 them with the spreader arrangement.

In use, the bottle is filled with suitable material. To pour a quantity out of the bottle, the latter is inverted and the tip pressed 55 upon any suitable object, thereby unseating the valve, and permitting a quantity of the contents to flow out through the discharge aperture. As soon as the pressure against the tip is released the spring support 17 seats 60 the valve and closes the aperture.

The device may be used to contain powders of various kinds, or may be used to contain other materials, such as soap, pastes, or shaving creams, or adhesives, mucilages,

and the like. When used as an adhesive container, the bottle is inverted, the tip is pressed upon the object to which it is desired to apply the adhesive, and after a sufficient quantity has been discharged upon said object, the flat spreader portion 24 may be used to spread the adhesive over the object.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new and desire to obtain by Letters Patent:

1. As a new article of manufacture, a container and a cap therefor, having a centrally apertured end portion, and an annular groove, a valve having a tip protruding from the container, and a flaring skirt, for closing the aperture, and a spring support for seating said valve around the aperture, said support having an annular base portion seated in said groove and held there by its own elasticity.

2. As a new article of manufacture, a container and a cap removably secured on said container, and having a centrally apertured end portion and an annular groove, a valve having a tip protruding from the container and a flaring skirt for closing the aperture, and a spring support for seating said valve around the aperture, said support having an annular base portion seated in said groove and held there by its own elasticity.

3. As a new article of manufacture, a container having a screw-threaded neck and a cap, having a screw-threaded portion fastened upon the threaded neck of the container, a centrally apertured end portion, and an annular groove, formed adjacent the screw threads, a valve having a tip protruding from the container and a flaring skirt for closing the aperture, and a spring support for seating said valve around the aperture, said support having an annular base portion seated in said groove and held there by its own elasticity.

4. As a new article of manufacture, a container and a cap removably secured on said container and having a centrally apertured end portion and an annular groove, a valve having a tip protruding from the container and a flaring skirt for closing the aperture, and a spring support for seating said valve around the aperture, said support having an annular base portion seated in said groove and held there by its own elasticity, and a yielding portion connected to the valve.

5. As a new article of manufacture, a container and a cap therefor having a shoul-

dered portion formed with an internal annular groove and a transverse groove extending therefrom, said cap having also a centrally apertured, tapered end portion, a
5 valve having a tip protruding from the container and a flaring skirt for closing the aperture, and a spring support for seating

said valve around the aperture, said support having an annular base portion seated in said groove and held there by its own elasticity, and having a part lying in said transverse groove and connecting the base portion with the valve. 10

PETER NEUKIRCHEN.
